UNITED STATES PATENT OFFICE.

ROBERT W. L. DUNN, OF TRENTON, NEW JERSEY.

CANDLE-HOLDER.

1,272,024.

Specification of Letters Patent.

Patented July 9, 1918.

Application filed December 30, 1916. Serial No. 139,895.

To all whom it may concern:

Be it known that I, ROBERT W. L. DUNN, a citizen of the United States, residing at Trenton, in the county of Mercer and State 5 of New Jersey, have invented certain new and useful Improvements in Candle-Holders, of which the following is a specification.

This invention relates to candle holders, the object of the invention being to provide an improved device of this character, 10 simple in construction and in operation, and which will be particularly efficient in use, it more particularly relating to an improvement in the base of the candle holder.

15 In the drawings accompanying and forming a part of this specification, Figure 1 is a vertical sectional view of the present improvement; Fig. 2 is a top view and Fig. 3 is a side view of the metal socket member 20 for the base of the candle; Fig. 4 is a view of the ring clamping member; Fig. 5 is a view of the improvement formed from a tube; and Fig. 6 is a view showing a sleeve adapted for use with Fig. 1 to maintain the 25 spring against side play in loading the holder. Similar characters of reference indicate corresponding parts in the several figures of the drawings.

The candle holder 2 may be of any desired 30 shape or material, it being shown herein as of barrel shape, and preferably of porcelain and provided with an inturned upper end 3 to limit the upward movement of the candle and also prevent running over of the 35 melted wax, and an outturned or flanged lower end 4 for the reception of the metal socket. The metal socket member comprises in one form thereof a bottom plate 5 and a plurality of upturned spring members 40 or prongs 6, forming a cup-shaped member and some of the prongs as 7, shown herein as three in number, are longer than the intermediate members. These members 45 7 are provided with inturned ends or clips 8 adapted to project over and be clamped to the bottom flanged end 4 of the candle holder. Located on the socket member is a ring 9, which is effective when the socket member is clipped over the flange of the 50 candle holder to secure it tightly thereon. By drawing the ring a short distance, the socket member may be readily removed from the bottom of the candle holder to permit the insertion of the candle. Located 55 within the barrel 2 with its lower end resting upon the bottom plate of the socket

member is a coiled spring 10 having a disk 11 at its upper end for engaging the bottom of the candle. By means of this spring the candle is properly fed and maintained in 60 position as it burns up. To maintain the ring against separation from the socket member the metal members or prongs 6 are bent outwardly as at 11 and the ends 65 form shoulders 12 upon which the ring will rest when withdrawn from around the clip prong members 7. The prongs may be bent to form, or provided with shoulders or recesses 14 to maintain the ring in place when the clips are secure to the flange of the candle holder. 70

From the foregoing, it will be observed that the present improved candle holder shown in Fig. 1 is made of but four members,—the holder, the spring, the prong-formed socket member, and the ring,—thus providing a very simple and efficient candle holder, which will permit the insertion of the candle from the bottom by the removal of the socket member, which can be quickly 75 and readily effected. The socket member is of sufficient size to fit into any suitable ornamental candle support as 20, which may be used.

For the purpose of facilitating the loading of the candle holder 2 with the candle and its spring, I have provided a sleeve or tube 20, which, as shown in Fig. 6 fits around the spring at the lower end thereof, where it rests in the socket member, and 80 this tube projects a sufficient distance above the socket member, so that it will telescope with the lower end of the porcelain candle holder when the spring has been compressed a certain distance, and thus prevent 85 the side play or wabbling of the spring during the final compression of the spring into position.

In the form shown in Fig. 5, the socket member is made in the form of a tube 21 100 having a bottom. Portions of the tube are pressed out to form the prongs 6 and 7 similar to those shown in the other figures of the drawings. In this form of the improvement however, the sleeve 20 and the 105 socket member shown in Fig. 1 are integral, so that by forming the socket member from a tube the advantages set forth in connection with the use of the sleeve shown in Fig. 6 are obtained without increasing the 110 number of the parts.

The various details may be more or less

changed without departing from the spirit or scope of the present improvement.

I claim as my invention:

1. A candle holder comprising a barrel-formed member having an integral flange at its lower end, a prong-formed member, some of the prongs being longer than others, the longer prongs having clips adapted to receive the flange, and means for holding the clips thereon.
  2. A candle holder comprising a barrel-formed member having a flange at its lower end, a spring-prong-formed member, the prongs thereof having clips for the reception of said flange, and a ring encircling said prongs for clamping the clips on the flange, said member having some of its prongs shaped to prevent the removal of the ring.
  3. A candle holder comprising a barrel-formed member having a flange at its lower end, a spring-prong-formed member, the prongs thereof having clips for the reception of said flange, and a ring encircling said prongs for clamping the clips on the flange, said member having means for preventing the removal of the ring and recesses for holding it in place when the clips are secured on the flange.
  4. A candle holder comprising a hollow member having a flange at its lower end and a member having a plurality of resilient prongs provided with clips for the reception of the flange, and means for clamping the clips on to the flange.
  5. A candle holder comprising a hollow member having a flange at its lower end and a member having a plurality of resilient prongs provided with clips for the reception of the flange, and means for clamping the clips on to the flange, said means comprising a shiftable ring.
  6. A candle holder comprising a hollow member having a flange at its lower end and a member having a plurality of resilient prongs provided with clips for the reception of the flange, means for clamping the clips on to the flange, said means comprising a shiftable ring, and means for preventing the removal of said ring.
  7. A candle holder comprising a hollow member having a flange at its lower end and a member having a plurality of resilient prongs provided with clips for the reception of the flange, means for clamping the clips on to the flange.
- on to the flange, said means comprising a shiftable ring, and means for maintaining the ring in position when the prongs are clamped to the flange.
8. A candle holder comprising a hollow member having a flange at its lower end and a member having a plurality of resilient prongs provided with clips for the reception of the flange, means for clamping the clips on to the flange, said means comprising a shiftable ring, means for maintaining the ring in position when the prongs are secured to the flange, and means for preventing the removal of the ring.
  9. A candle holder comprising a hollow member having a flange at its lower end, a member having a plurality of resilient prongs provided with clips for the reception of the flange, means for clamping the clips on to the flange, a spring in said members, and a sleeve carried by the prong-formed member and adapted to telescope with the hollow member.
  10. A candle holder comprising a hollow member having a flange at its lower end, a sleeve-formed member adapted to project into said hollow member and having a plurality of resilient prongs provided with clips for the reception of the flange, and means for clamping the clips on to the flange.
  11. A candle holder comprising a hollow member having a flange at its lower end, a sleeve-formed member adapted to project into said hollow member and having a plurality of resilient prongs provided with clips for the reception of the flange, and means for clamping the clips on to the flange and comprising a shiftable ring.
  12. A candle holder comprising a hollow member having a flange at its lower end, a sleeve-formed member adapted to project into said hollow member and having a plurality of resilient prongs provided with clips for the reception of the flange, and means for clamping the clips on to the flange and comprising a shiftable ring, said sleeve member having means for preventing the removal of the ring.

Signed at Trenton, N. J., this 27th day of December, 1916.

R. W. L. DUNN.
